[57] CLAIM

The ornamental design for a mudflap, as shown and described.

DESCRIPTION

FIG. 1 is a perspective view of an mudflap showing our new design;

FIG. 2 is a front elevational view;

FIG. 3 is a rear elevational view;

FIG. 4 is a top plan view;

FIG. 5 is a bottom plan view;

FIG. 6 is a right side elevational view;

FIG. 7 is a left side elevational view;

FIG. 8 is an enlarged fragmentary cross section view taken along line 8—8 between the planes A—A and B—B in FIG. 2;

FIG. 9 is an enlarged fragmentary perspective view of the upper left portion of the front unit of the mudflap; and,

FIG. 10 is an enlarged fragmentary perspective view of the lower right front portion of the rear unit of the mudflap in disassembled condition with the flexible interlocking end panel rotated ninety degrees to a vertical unlocked position.
